ELECTRIC LAMP

Manuel Diaz Fernández, Habana, Cuba

**Application November 20, 1937, Serial No. 175,624
In Cuba January 14, 1937**

In Cuba January 14, 1937

This invention relates to lamps and particularly to an improved electric lamp, an object being to provide a construction which will give the desired light and which may be mounted on a stand or connected with any desired piece of furniture.

Another object of the invention is to provide an electric lamp having a suitable supporting frame which will protect the bulb, and formed 10 to cause the light to shine in the desired direction.

A further object, more specifically, is to provide an electric lamp using a tubular bulb and provided with a reflector which may be rotated around the bulb so as to cause the light to shine in any desired direction.

In the accompanying drawings—

Figure 1 is a perspective view of a frame constructed in accordance with the present invention;

Figure 2 is a longitudinal vertical sectional view through a complete lamp disclosing an embodiment of the invention;

Figure 3 is a transverse sectional view through Figure 2 approximately on the line 3-3;

Figure 4 is a perspective view with certain parts broken away and illustrating one of the rings shown in Figures 1 and 2;

Figure 5 is a perspective view of a second ring embodying certain features of the invention; Figure 6 is a perspective view of the reflector.

Figure 6 is a perspective view of the reflector or shade shown in Figure 2;

Figure 7 is a perspective view of the protecting ring shown in Figure 2; and

Referring to the accompanying drawings by

40 numerals, 1 indicates a frame which is formed with a plurality of tubes 2 connected with the respective rings 3 and 4. This frame is supplied with a number of identically shaped rings 5, as shown in Figure 2, said rings being mounted on top of ring 3 and clamped in place by any desired number of threaded rods 6. The top plate 7 may, 45 be solid throughout or formed into a ring as preferred. Preferably this plate or ring is solid throughout so as to receive a threaded member 8 whereby the lamp may be connected to a bracket or piece of furniture. The upper ends of the 50 rods 6 are covered with ornamental caps 9, while the lower ends are threaded into the respective tubes 2 so as to clamp the plate 7, ring 5 and ring 3 together and to these tubes.

It will be noted that the ring 3 is provided with an annular rabbet or groove 10 which coacts with

the upstanding flange of a ring 11 carried by the supporting ring 12 of the shade or reflector 13. The lower ring 4 is clamped to the various tubes 2 by a plurality of threaded rods 14, which rods at their lower ends carry the respective rings 15, 16, 17 and 18. The member 18 while functioning as a ring also functions as a bottom for the lamp as this ring is filled in so as to present really a recessed plate carrying a tubular threaded member 19 which may be screwed on to a stand or any other desired piece of furniture. The ring 16 is also formed as a recessed plate and, consequently, there is provided a chamber 20 in which the body of the switch 21 is mounted. The thumb member 22 of the switch extends through the plate 18 so that the switch may be turned on and off as desired. Lead-in wires 23 and 24 extend to the tubular member 19 and to the switch 21 and to the base of the socket 25. One wire naturally extends to the casing 26 of the socket and the other to the switch 21 so as to provide a proper circuit for the bulb 28. The bulb 28 is elongated and tubular as illustrated in Figure 2. When in use the bulb 28 is screwed into the socket 25 and may be unscrewed at any time. It will be evident that the current may be turned on and off by actuating the switch 21.

A protecting sleeve or rim 29 has its lower end embedded in the annular ring 15 and its upper end embedded in the ring 4. This not only protects the socket 25 and associated parts but presents a nice appearance to the lower part of the lamp structure. It will also be noted that the lower end of the threaded rods 14 are provided with caps 30 and that the upper part of the ring 4 is provided with an annular rabbet or groove 31 in which the flange 32 of a ring 33 extends. The ring 33 is secured in any desired manner to the ring 34 of the shade or reflector 13. This shade or reflector 13 is shown particularly in Figure 6. The ring 34 is at the bottom while ring 12 is at the top and carries the flanged ring 11 which fits in the groove 10 of ring 3. A plurality of tubes 35 connect rings 12 and 34 and these tubes are secured to the respective rings by respective threaded rods 36 and 37 as shown in Figure 2. Suitable caps 38 and 39 cover the exposed ends of these rods. In the drawings three tubes 35 have been shown but a greater or less number could be used without departing from the spirit of the invention.

As shown in Figure 3 an arc-shaped reflecting surface 40 is provided. This surface may be in one piece or may be made in two or more parts and properly secured in place. Preferably this 55

shade member or reflecting structure is a half circle in cross section so that approximately half of the bulb 28 is covered. By reason of the flanges on rings 11 and 33 the shade 13 is rotatably mounted and may be moved around the bulb 28 to any desired position so as to cause illumination from the bulb to be projected in the desired direction. If desired, however, the rings 12 and 34 could be fixedly secured to the rings 3 and 4.

The various rings 5, 3, 12 and 15 and their associated means may be made from glass, "Gallalith", metal, or other desired material. The tubes and rods are preferably made from metal so that they may clamp the various other parts properly in assembled position.

I claim:

1. An electric lamp comprising a frame formed with a top ring, a bottom ring, a pair of spaced intermediate rings, all of said rings being of the same diameter, a plurality of rods extending through all of said rings, means acting on said rods and rings for connecting said rings to said rods, rotatable annular members arranged between the said intermediate rings, a plurality of tubes acting on said annular members for holding the annular members against said intermediate rings, a bolt extending through said tubes for clamping said annular members against said tubes for presenting a rotatable reflector frame, means secured to said rotatable frame acting as a reflector, means coacting with the first men-

tioned frame for forming a base, an electric bulb socket arranged in said base, and means for directing current to said socket, said means including a hand-actuated switch projecting below said base.

2. An electric lamp of the character described including a main frame, an auxiliary frame adapted to rotate around said main frame, a reflector carried by said auxiliary frame, a base secured to said main frame, an electric socket carried by said base, means including a switch for directing lead-in wires to said electric socket, and means at the end of said frame opposite that carrying the base presenting a housing for loosely receiving the end of the bulb screwed into said electric socket.

3. An electric lamp of the character described including a main frame formed of a plurality of rods, a pair of spaced ring members adjacent each end of said rods, annular rotatable members arranged adjacent the two inner rings of said pair of rings, a plurality of tubes spacing said annular members and holding the same in operative position, screw members extending through said annular members into said tubes for clamping the annular members rigidly to the tubes, a reflector carried by said annular members and said tubes and a socket arranged in the lower part of said frame, and means for directing lead-in wires to said socket.
